UNITED STATES PATENT OFFICE.

JOHN H. HUGHES, OF GREENWICH, CONNECTICUT, ASSIGNOR OF ONE-HALF
TO FREDERICK A. HUBBARD, OF GREENWICH, CONNECTICUT.

THIRD-RAIL SYSTEM.

SPECIFICATION forming part of Letters Patent No. 738,721, dated September 8, 1903.

Application filed April 30, 1903. Serial No. 154,976. (No model.)

To all whom it may concern:

Be it known that I, JOHN H. HUGHES, a citizen of the United States of America, and a resident of Greenwich, in the county of Fairfield and State of Connecticut, have invented certain new and useful Improvements in Third-Rail Systems, of which the following is a specification.

My invention relates to protected third or 10 conducting rails for electric railways; and it consists of an improved construction of said rails for economy of material, disposition of same for strength, and facility of mounting, securing, and insulating the same.

15 It also consists of improvements in the mounting apparatus, as hereinafter described, reference being made to the accompanying drawings, in which—

Figure 1 is a vertical transverse section of 20 my improved third-rail system. Fig. 2 is a detail in side elevation. Fig. 3 is a detail in vertical transverse section, showing a slight modification of the gripping and holding devices of the rail-mounting. Fig. 4 is a detail in transverse section, showing a modification of the rail-insulating device.

The rail is in its essential form of transverse section an angle-bar whereof one flange 25 a is of considerable greater width than the other flange b, and the web of flange a has an intermediate offset c, whereby flange a, being the vertical support of flange b, hereinafter called the "rail-head," has its lower margin a', whereby it is mounted for support, located 30 intermediately of the lateral range of the rail-head for facilitating limited lateral dimensions of the structure, as will appear further on. In one form of construction the rail has the T-head e of the lower edge and the side 35 ribs or flanges f intermediately of said head e and the offset c, adapting it to be substantially clamped between jaws g of supporting-brackets h, adapted for being seated on and secured to any suitable foundation and provided with suitable clamping-bolts i, said 40 jaws being either integral parts of the brackets, suitably chambered on the gripping-faces, as indicated at j, for the application of suitable insulating material k, Figs. 1 to 3, and, 45 if desired, separate parts g², made entirely of insulating material, as in Fig. 4. When such

separate jaws, as g², are used, they will be confined against vertical displacement by ribs g³ of the vertical plates of the brackets. In a slightly-modified but equivalent form of 55 construction the rail has side ribs or flanges l near the lower edge of flange a, and the jaws g are notched in the gripping-faces to correspond with said ribs, so as to receive them with the required insulating material k, like 60 clamping-bolts i being used. It will be seen that in both of these forms there is powerful support against vertical displacement in either direction, as well as against lateral displacement, and thus these ribs serve both 65 for mounting and strengthening the rail. As the clamping-bolts of the rail-holding brackets have to be below the jaws for avoiding possible interference with electric currents, the edges of the base-flanges of the 70 brackets are placed in contact with each other at h' for positive resistance to the stress of the clamping-bolts and causing the full effect of such stress on the jaws.

The conducting-shoe m is carried on a 75 bracket n, which, it is to be understood, is suitably attached to any suitable part of the car, the arrangement being such that the upper surface of the shoe makes contact with the under surface of the rail-head b to facilitate the application of a protective guard over the top and the outside of the rail. For such a guard I provide a continuous angle structure of 80 wood strips o p, suitably reinforced at the angle of junction q by metallic angle-brackets, as s, placed outside and suitably bolted on, said brackets being reinforced with strengthening-ribs t in the locality of the angle, the chief need of reinforcement being in the location of the joint q. This guard is mounted 85 on the outer vertical surfaces of the outer brackets h by bolts u in the lower margin of strip o, said bracket being preferably notched at v to receive said bolts laterally, said bolts being too long to be inserted through holes 90 on account of interference with the rail, and the strips o are notched at w to clear the upper ends of the bracket-stiffening flanges v'. On the inner margin of the top-strip p of the guard is a drop-rib x, of wood or other 95 protective material, guarding against contact 100 with the inner edge of the rail-head b.

It will now be seen that the lateral offset c in the vertical rail-flange a in the direction of the vertical member of the protective guard enables wider dimensions of the rail-head within a given breadth of the guard and with the part a' of the vertical flange properly centered within the gripping-jaws of the supporting-brackets of given dimensions, besides affording greater strength of the rail with a minimum of metal.

What I claim as my invention is—

1. The improved third rail consisting of the angle-bars comprising the vertical supporting-flange and the horizontal rail-head, said vertical flange having the lateral offset and the side ribs or flanges for stiffening and for mounting and securing the rail.
2. The combination with the rail consisting of the angle-bar comprising the vertical supporting-flange and horizontal rail-head, said vertical flange having the side ribs or flanges for stiffening and for mounting and securing the rail, of the supporting-brackets having the gripping-jaws adapted to clamp said rails with intervening insulating material, and suitable clamping-bolts.
3. The combination with the rail consisting of the angle-bar comprising the vertical supporting-flange and horizontal rail-head, said vertical flange having the side ribs or flanges for stiffening and for mounting and securing the rail, of the supporting-brackets having insulated gripping-jaws adapted to clamp said ribs, said jaws applied to the vertical bracket-plates, having ribs for confining said jaws against vertical displacement.

4. The combination with the rail consisting of the angle-bar comprising the vertical supporting-flange and horizontal rail-head, said vertical flange having the lateral offset and the side ribs or flanges for stiffening and for mounting and securing the rail, of the supporting-brackets having the gripping-jaws adapted to clamp said rails with intervening insulating material and suitable clamping-bolts.

5. In a third-rail system the combination of the rail consisting of the angle-bar comprising the vertical supporting-flange and the horizontal flange-head, supporting-brackets and clamping-jaws carrying the rail, the angle protective guard attached to and supported on the outside brackets, and the drop-guard of the inner edge of the top of the angle-guard.

6. In a third-rail system the combination of the rail consisting of the angle-bar comprising the vertical supporting-flange and the horizontal flange-head, and the supporting-brackets and clamping-jaws carrying the rail, said brackets having bearing contact with each other, of the base-flanges for positive resistance to the stress of the clamping-bolts, and full effect of such stress on the jaws.

Signed at Greenwich this 20th day of April, 1903.

JOHN H. HUGHES.
